UNITED STATES PATENT OFFICE

161,711

TOOL FOR CORRECTING WHEEL CASTER AND CAMBER

Albert Romak, Chicago, Ill., assignor of one-fourth to I. Irving Silverman, Chicago, Ill.

Application July 23, 1949, Serial No. 4,088

Term of patent 14 years

(Cl. D54—13)

To all whom it may concern:

Be it known that I, Albert Romak, a subject of Romania, and resident of Chicago, Illinois, in the county of Cook and State of Illinois, have invented a new, original, and ornamental Design for a Tool for Correcting Wheel Caster and Camber, of which the following is a specification, reference being had to the accompanying drawings, forming a part thereof.

Fig. 1 is a perspective view of a tool for correcting wheel caster and camber, showing my new design.

Fig. 2 is a side elevational view of the same.

Fig. 3 is a top plan view of the same.

Fig. 4 is a bottom plan view of the same.

I claim:

The ornamental design for a tool for correcting wheel caster and camber, as shown.

ALBERT ROMAK.
